Attorney:

UNITED STATES PATENT OFFICE.

JOHN POLHEMUS, OF NEW YORK, N. Y.

PRINTER'S QUOIN.

SPECIFICATION forming part of Letters Patent No. 296,056, dated April 1, 1884.

Application filed April 26, 1883. (No model.)

To all whom it may concern:

Be it known that I, JOHN POLHEMUS, a citizen of the United States of America, residing at New York city, in the county of New York 5 and State of New York, have invented certain new and useful Improvements in Printers' Quoins; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 This invention relates to certain new and useful improvements in printers' quoins; and it has for its object to provide a quoin with means whereby the shooting-stick which is employed to drive the quoin in place can have 20 a firm hold upon the same; and to this end it consists in providing an ordinary wedge-shaped quoin with central recesses and grooved ends, as will be hereinafter more fully set forth, and pointed out in the claim.

25 In the annexed drawings, which illustrate my invention, Figure 1 is a perspective view of one of the coins. Fig. 2 is a plan view, showing the same applied in a chase.

In the accompanying drawings, A represents 30 a printer's quoin, which is preferably

constructed of metal in the usual manner—that is to say, wedge-shaped—which quoin is provided on its two parallel sides or on its top and bottom with grooves or recesses of any required depth or shape, these recesses 35 being represented by the letters *a a*. The ends of these grooves or recesses *a a* are concave to form a better bearing for the end of the shooting-stick. The ends *c c* of the quoins are grooved or concave, as shown. 40

With a quoin constructed as hereinbefore described central as well as end bearings for the shooting-stick are provided, and the same being curved, as shown, will prevent the shooting-stick being displaced when struck with a 45 mallet.

Having thus described my invention, what I claim as new, and desire to secure by Letters Patent, is—

As a new and improved article of manufacture, a printer's quoin having the following characteristics: a wedge-shaped body, with vertical concave ends, and recesses with curved ends on each of its parallel sides, substantially 50 as shown, and for the purpose set forth.

JOHN POLHEMUS.

In presence of—

WILLIAM V. H. HICKS,
A. SIDNEY DOANE.
